UNITED STATES PATENT OFFICE.

FRANK W. HOMAN, OF PHILADELPHIA, PENNSYLVANIA.

TURNED SHOE.

1,350,156.

Specification of Letters Patent. Patented Aug. 17, 1920.

Application filed February 11, 1920. Serial No. 357,920.

To all whom it may concern:

Be it known that I, FRANK W. HOMAN, a citizen of the United States, residing at Philadelphia, in the county of Philadelphia, 5 State of Pennsylvania, have invented a certain new and useful Improvement in Turned Shoes, of which the following is a specification, reference being had therein to the accompanying drawings.

10 The invention enables me to effect a large economy and reduction of cost in the manufacture of turned shoes having covered heels, *i. e.*, heels furnished with coverings of leather, cloth, or felt.

15 The drawings show in longitudinal section in Figure 1 the lower portion of a shoe embodying the invention.

Fig. 2 is a view showing the sole and heel of the shoe of Fig. 1, as connected together prior to being lasted, with a small part of the toe-portion broken away.

Fig. 3 is a top view of the parts that are shown in Fig. 2.

Fig. 4 is a view representing in longitudinal section a portion of a last with the shoe thereon, showing the shoe as it appears after being lasted and stitched, and also trimmed, but before being turned.

Fig. 5 is a bottom view of the shoe in the stage shown in Fig. 4.

Referring to the drawings:

The sole 1 is considerably shorter than the shoe, it being only a little longer than the forepart and shank; that is to say, it is just long enough to enable its rear end-portion to lie upon the forward portion of the heel 2 and extend over such portion sufficiently to receive one or more tacks 3, 3, which fasten the sole and heel together. 35 Preferably two or more tacks are employed, in order to prevent the short sole and the heel from swinging out of line with each other. The sole is channeled at 4, along both side-margins thereof, and around the toe-portion.

The portion of the heel-covering 5 that extends above the top of the heel provides a projecting flange 5^a around the back and at both sides of the heel. At the heelbreast 50 the top marginal portion 5^b of the heel-covering is folded over backward on top of the heel, and is overlaid by the overlapping portion of the sole.

In lasting the shoe, I use a last L, Fig. 4, having the heel-part thereof recessed to accommodate the heel 2. I apply thereto

the combined sole and heel, with the flesh side of the sole turned uppermost and the heel entered into the recess of the last, as in Fig. 4. The upper 6, counter-stiffener 7, 60 and lining 8 which covers the counter-stiffener in the finished shoe, are applied to the lasted sole and heel as shown in Figs. 4 and 5. Around the fore-part of the shoe and at the shank thereof the sole and upper are 65 connected together by means of stitches 4^b engaging with the lip 4^a of the channel and the flange of the upper. At the heel-end of the shoe the flanges of the heel-covering, upper, counter-stiffener, and counter-lining, 70 are connected together by stitches 4^c extending around the heel.

Following the stitching, the shoe is trimmed, turned, re-lasted, and subjected to the usual finishing operations. At f, 75 Fig. 1, is shown a shoe-bottom filler which occupies the hollow in the turned shoe, within the inturned flange of the upper, and at s, same figure, is indicated a lining or removable insole.

My invention enables me to use in making a shoe of a given size-number a sole much smaller than required in making a shoe of ordinary construction of that size-number, namely no larger than one such as, in the case of a shoe of usual construction, is used for a much smaller size-number. For instance, in making a middle-size ladies' shoe, either a No. 4 or a No. 5, I use only a 13 size misses' sole, such 80 being the smallest size of misses' sole, making a difference in cost equal at present prices to one-third of the cost of the pair of soles used in making a pair of shoes.

Preferably the sole, prior to attachment 95 to the heel, is so cut and shaped at its heel-end as to reduce in width the portion thereof which laps over upon the top of the heel, and produce shoulders at opposite sides to determine the size of the sole 100 (measured from tip of toe-end to heel-end), and to guide in combining the sole and heel and getting the heel properly squared with reference to the sole before the two are fastened together.

The object of a feature of invention to which I shall now refer is to prevent the covering of the heel from being loosened from the sides of the heel in the process of stitching the parts of the shoe together at 110 the heel. Such loosening would render the heel of the finished shoe more or less un-

sightly and also open to the objection of being free to move cross-wise of the shoe, or at any rate presenting the appearance of loose attachment. This feature consists in a piece 10 of cloth, or other suitable material, capable of meeting the requirements of the purpose for which it is used, attached to the base of the heel, (the upper surface in the finished shoe) and having a marginal portion 10^a which projects upward around the sides and back of the heel. The stitches 4^c at the heel pass through the said projecting flange. The said piece of material resists the strain in stitching which tends to separate the heel-covering from the vertical portion of the heel, and it holds the heel from lateral play in the case of the finished shoe. It is cemented to the base of the heel, and, in addition, the tacks 20 which unite the heel and sole together pass through it so as effectually to prevent it from pulling over sidewise in any direction. I also preferably make a line 11 of stitches around the base of the heel, uniting the top-flanges of the heel-covering and the marginal flange of the stay-piece together, prior to fastening the heel and sole together in the preliminary assembling of these two parts together.

30 What is claimed as the invention is,—

1. A shoe comprising a covered heel, a forepart-and-shank sole-section partly overlapping by its rear extremity the forward portion of said heel and attached thereto

by fastening means engaging with the overlapping portions, and an upper with which the combined sole-section and heel are connected by fastenings engaging with the sole-section and passing through the upper portion of the heel-covering around the 40 sides and back of the heel.

2. A shoe comprising a covered heel having a stay-piece fastened to its top surface, a forepart-and-shank sole-section partly overlapping by its rear extremity the forward portion of said heel and attached thereto by fastening means engaging with the overlapping portions, and an upper with which the combined sole-section and heel are connected by fastenings engaging with 45 the sole-section and passing through the upper portion of the heel-covering and the margin or flange of the said stay-piece around the sides and back of the heel.

3. A shoe having a heel furnished with 50 a covering that extends above the top surface of the heel, and a stay-piece that is fastened to the said top surface, and having also the shoe-upper connected with the upper margin of said heel-covering and 55 with the margin of the stay-piece, around the sides and back of the heel.

In testimony whereof I affix my signature in presence of two witnesses.

FRANK W. HOMAN.
